UNITED STATES PATENT OFFICE.

OLIVER E. BUCKLEY, OF MAPLEWOOD, NEW JERSEY, ASSIGNOR TO WESTERN ELECTRIC COMPANY, INCORPORATED, OF NEW YORK, N. Y., A CORPORATION OF NEW YORK.

LOADED-SUBMARINE-CABLE TELEGRAPH SYSTEM.

Application filed August 14, 1924. Serial No. 731,897.

This invention relates to submarine telegraphy over a loaded submarine cable, and more particularly to a method for eliminating distortion due to magnetic hysteresis in 5 the loading material.

In a loaded submarine cable, as for example, in the type of cable described in applicant's Patents 1,586,874 and 1,586,875, granted June 1, 1926, signals are attenuated 10 and distorted in a manner different from that in ordinary non-loaded cables. The addition of inductance serves to counteract in a degree the effect of the capacity in attenuating and distorting the signals, but at the 15 same time introduces new sources of distortion. These arise chiefly from the effective resistance introduced by eddy currents and hysteresis in the nickel-iron alloy or other loading material used for adding inductance. 20 The effect of eddy currents is to cause greater attenuation of the high frequency components of the signals. This type of distortion may be reduced by the use of thin laminations of loading material and by compensating networks which tend to restore the 25 various frequency components to their original relative amplitudes.

The effect of hysteresis is only felt with 30 relatively great strength of sending current and is introduced principally at the sending end of the cable where the current is large compared to its value at the receiving end. This is because hysteresis loss increases rapidly with increase of current strength and 35 disappears when the current amplitude approaches zero. The distortion introduced by hysteresis is peculiar in that with certain types of signals such as, for instance, signals in the standard three-element cable 40 code it is asymmetrical as will be explained hereinafter. One way to avoid hysteresis distortion is to use a low sending voltage which will result in small current strength in the cable conductor. However, to secure 45 the maximum speed of operation of a cable it is desirable to use as high a sending voltage as considerations of safety will permit. As the sending voltage is increased, using the standard method of operation with three 50 element signals of the cable code, the effect of hysteresis becomes more and more serious and finally sets a limit to the sending voltage which can be used.

An object of the present invention is to 55 obviate distortion due to hysteresis.

To this end telegraph signals are transmitted over a loaded cable by means of a two-element code. In such a code positive and negative impulses of equal amplitudes are impressed upon the cable for each signal 60 element. Spaces are indicated by current of one polarity, while dots and dashes are indicated by current of the opposite polarity. Dots are distinguished from dashes by the time interval of the application of the 65 impressed potential. The principle of operation will be explained hereinafter.

The novel features which are considered characteristic of this invention are set forth with particularity in the appended claims. 70 The invention, both as to its organization and operation together with other objects and advantages thereof, will be further explained hereinafter, having reference to the accompanying drawing, consisting of the 75 following figures:

Fig. 1 is a circuit diagram showing schematically one embodiment of the invention.

Fig. 2 is a typical B-H curve of the 80 magnetic material used to load the cable of Fig. 1.

Fig. 3 illustrates wave forms involved in signaling with the two-element code.

Fig. 4 illustrates wave forms involved in signaling with a three-element code. 85

Proceeding now to a detailed description of one embodiment of the invention, and referring first to Fig. 1, a loaded cable 5 constitutes a transmission circuit between sending apparatus S and receiving apparatus R. 90 Sending apparatus S is adapted to transmit signals according to a two-element code. Current is supplied by battery 6 under the control of relays 7 and 8, the armatures of which determine the polarity which is impressed upon the cable 5. The relays 7 and 8 are energized simultaneously by current from battery 9 when key 10 is depressed. The sending end condenser 11 is connected into the transmission circuit between the 100 armature of relay 7 and the cable 5. With key 10 open (as shown) negative potential from battery 6 is impressed upon the sending end condenser 11. When key 10 is closed and relays 7 and 8 are energized to attract 105 their armatures, positive potential is impressed upon the sending condenser 11.

At the receiving terminal, electron discharge devices 12 and 13 are employed to 110 amplify the incoming signals for operating

a recording device 14, which may be a syphon recorder as indicated. Wave shaping networks 15 are employed in the manner described in the copending applications of

5 Oliver E. Buckley *supra*. Other suitable receiving terminal apparatus, such as that disclosed in a patent to A. M. Curtis 1,586,970, granted June 1, 1926, may be used.

The cable 5 is preferably a loaded conductor 10 loaded with a nickel-iron alloy, in the manner fully described in applicant's Patents 1,586,874 and 1,586,875 *supra*. As hereinbefore pointed out, distortion due to hysteresis becomes important because of the 15 high speeds of signaling involved. The manner in which distortion due to hysteresis is eliminated according to this invention will now be explained in connection with Figs. 2, 3 and 4.

20 In Fig. 2, a typical hysteresis loop or B—H curve is shown. When a two-element code is used for signaling, the wave shape of the applied potential will be like that shown in curve A of Fig. 3. Due to the sending condenser 11, the wave shape of the current 25 near the sending end of the cable 5 will be substantially that shown in curve B of Fig. 3.

Suppose now that the field H of Fig. 2 30 corresponds to the current I in curve B of Fig. 3. Then the pulse 1 will carry the magnetization of the loading material through the curve c d a, assuming that it already has a negative remanence. The next impulse 2, being of opposite sign, will carry it through the curve a b c. The third impulse will carry it through the curve c d a again. Since successive impulses are of opposite 40 polarity and since all of the impulses give the same degree of change of induction, each impulse will give the same induced electromotive force and the same strength of propagated signal. There will, therefore, be no 45 asymmetrical magnetic distortion due to hysteresis.

Considering, however, the case of signaling by means of three-element signals as used in the standard cable code, the wave 50 shape of the applied electromotive force being shown by curve C of Fig. 4, the wave shape of the current near the sending end of the cable 5, due to the action of the sending end condenser 11, will be that shown in curve D of Fig. 4. Starting again with a 55 remanence c as before, impulse 1 will carry the magnetic material through the curve c d a. The second impulse will carry it through the curve a b c. Impulse 3 will carry it again through curve c d a and impulse 4 through curve a b c. The impulse 5, however, being 60 of the same polarity as in pulse 4, will carry the material only over the dotted curve c f c, giving only a very small change of induction 65 relative to that given by impulse 4, and consequently a relatively weak transmitted

impulse along the cable. The same effect will occur again at impulse 7 following impulse 6, both of which are of the same polarity.

The effect upon the received signals will 70 now be described. In either type of signaling there will be distortion in the received signals, which will need to be corrected. As will hereinafter, however, appear this can be easily accomplished in the case of two element working. 75

The difficulty encountered in three element operation is caused by the sending end of the cable acting as a low inductance loaded cable when the current in the cable 80 changes from maximum to zero or when the current changes from zero to a maximum of the same sign as the preceding maximum, while, in the cases where the current changes from zero to a maximum of sign opposite to the preceding maximum, the cable acts as a high inductance loaded cable. In the case of the current impulses involved in the two-element code, as shown in Fig. 3 curve B, this means that the first half of each of the 85 pulses, that is the change from zero to maximum current, will be transmitted as over a cable of much higher inductance than the apparent inductance of the actual cable, while the second half of each pulse, that is a 90 change from maximum to zero current, will be received as though it had been transmitted over a cable of smaller inductance than that of the actual cable. There is therefore distortion present in the two-element system of 95 signaling, but it affects all signals alike and therefore does not cause confusion in interpreting the received message. There will probably be involved in each signal a 100 small irregularity which probably would show up more at higher values of signaling speeds than at the lower.

Referring to Fig. 4 curve D, it can be seen that in the case of signals in the three-element code, there will be, in addition to the distortion just described, an additional distortion due to the fact that entire current pulses of the type 5, 6 or 7, 8 are received as though they had been transmitted over a low inductance cable. This means that at every 110 point in the message where the current changes from zero to a maximum value of opposite sign from the preceding signal pulse, the initial height and slope of such a signal will be different from that of the other signals and this distortion cannot be corrected by shaping networks without distorting the remaining signal pulses. The point at which this distortion takes place 115 is exactly the place where maximum clearness is necessary.

A type of distortion will thus be introduced in three-element working which would be absent with two-element working. From the foregoing description it is seen that 120 125 130

troublesome hysteresis distortion is eliminated by the use of a two-element code in connection with loaded submarine cables.

The invention is not limited to the specific elements shown in Fig. 1. Modifications thereof will be obvious to those skilled in the art. The scope of the invention is defined by the appended claims.

What is claimed is:

- 10 1. The method of signaling over a submarine cable loaded with magnetic material for increasing the inductance thereof, said magnetic material introducing hysteresis loss at the magnetic densities involved in transmission, which comprises employing a two-element code for transmission.
- 20 2. The method of reducing signal distortion when signaling over a submarine cable loaded with magnetic material for increasing the inductance thereof, said material being such as to introduce hysteresis loss at the magnetic densities involved in transmission, which comprises applying potential impulses to the cable in such order that each 25 of the resultant current impulses causes the loading material to pass through a magnetization cycle substantially identical with the cycle resulting from any and every other current impulse of the same polarity.
- 30 3. In a submarine telegraph system employing for transmission a submarine cable loaded with magnetic material of sufficient permeability to increase the possible signaling speed as compared with an unloaded cable, the method of reducing signal distortion caused by hysteresis effects in the loading material which comprises applying to

the cable successive signaling impulses of alternately opposite potential but of equal amplitude.

40

4. In a signaling system, a long cable, magnetic material used to load said cable, means to apply successive impulses of direct current to said loaded cable for signaling, successive impulses being of opposite 45 polarity but equal amplitudes, and receiving means for said signals.

5. In a submarine telegraph signaling system, a long submarine cable loaded with magnetic material having appreciable hysteresis at the current amplitudes used for telegraphing, sending apparatus adapted for applying impulses of current to said cable according to a two-element code, and receiving apparatus for receiving said signals. 55

6. In a submarine telegraph signaling system, a submarine cable loaded with a nickel-iron alloy having a permeability appreciably higher than that of iron, sending apparatus adapted for applying impulses of current to 60 said cable according to a two-element code, and receiving apparatus for receiving said signals.

7. In a submarine telegraph signaling system, a submarine cable at least a thousand 65 miles long loaded with nickel-iron alloy, sending apparatus adapted for applying impulses of current to said cable according to a two-element code, and receiving apparatus for receiving said signals. 70

In witness whereof, I hereunto subscribe my name this 11th day of August, A. D., 1924.

OLIVER E. BUCKLEY.
